JOSIAH SHEPARD, OF NEW BRITAIN, CONNECTICUT.

Letters Patent No. 71,232, dated November 19, 1867.

IMPROVEMENT IN KITE-FRAMES.

The Schedule referred to in these Letters Patent and making part of the same.

TO ALL WHOM IT MAY CONCERN:

Be it known that I, JOSIAH SHEPARD, of New Britain, in the county of Hartford, and State of Connecticut, have invented, made, and applied to use, a certain new and useful Improvement in Kite-Frames; and I do hereby declare the following to be a full, clear, and exact description of the said invention, reference being had to the annexed drawing, making part of this specification, wherein—

Figure 1 is an elevation of the kite-frame complete, and

Figure 2 is a separate view of the saddle.

The object of my invention is to provide a light and strong frame adapted to being taken apart and put in a small compass for transportation.

The said invention consists in a frame of tempered steel or metal ribs, secured by a central saddle-piece, through holes in which the metal ribs are passed, and I make use of small tips, to which is attached the cord that borders the kite and sustains the edges of the thin paper or other fabric. The ribs can be sprung out of the tips and withdrawn from the saddle-piece, so as to be packed together, and the covering can be rolled up or folded. By this construction the kite can be made very durable, and can be carried with ease to the most convenient place for flying it and there put together.

In the drawing, *a* is a saddle-piece, formed of thin sheet metal, and perforated with two holes for each rib, so that said ribs may be passed through the holes and intersect each other, the saddle being bent so as to allow one rib to pass by the other. These ribs *b b* and saddle *a* are to be of a proper size in proportion to the kite, and the ribs made of tempered steel or other wire. The tips *c c* are small pieces of bone or metal, each having a hole to pass the cord *d* that borders the kite, and a hole to receive the end of the rib.

The mode of constructing the kite and taking it apart for transportation or putting it together for use will be apparent from the foregoing.

At the holes where the cords forming the "belly-band" are tied to the ribs small washers of thick paper should be attached to the covering of the kite to prevent the same tearing, and the cords themselves may be extended to the respective tips and there made fast, to prevent the loop slipping along on the smooth metal rib.

What I claim, and desire to secure by Letters Patent, is—

1. A kite-frame formed of ribs of tempered steel or metal wires, as set forth.
2. The saddle-piece *a*, made in the manner as set forth, for receiving the wire ribs, as specified.
3. The tips made with holes for the cord forming the border of the kite and with holes for receiving the ends of the ribs, as set forth.

In witness whereof I have hereunto set my signature this sixth day of April, 1867.

JOSIAH SHEPARD.
